UNITED STATES PATENT OFFICE.

HOMER A. SANDERSON, OF DETROIT, MICHIGAN, ASSIGNOR TO UNDERWOOD TYPEWRITER COMPANY, OF NEW YORK, N. Y., A CORPORATION OF NEW JERSEY.

TYPE-WRITING MACHINE.

No. 827,942.

Specification of Letters Patent.

Patented Aug. 7, 1906.

Application filed November 23, 1905. Serial No. 289,473.

To all whom it may concern:

Be it known that I, HOMER A. SANDERSON, a citizen of the United States, residing in Detroit, in the county of Wayne and State of Michigan, have invented certain new and useful Improvements in Type-Writing Machines, of which the following is a specification.

This invention relates to the ribbon-winding mechanisms of type-writing machines, and particularly to means for automatically reversing the direction of winding.

The principal object of the invention is to provide a compact, inexpensive, and simple mechanism which may readily be placed upon machines as at present manufactured, particularly those of the front-strike variety, in which the spools are mounted in front of the platen, one at each side of the printing-point.

The accompanying drawing is a perspective view showing my improvements applied to an "Underwood" front-strike writing-machine.

In said machine types 1 strike through a ribbon 2 against the front side of a platen 3, the ribbon being wound upon spools 4 5 and threaded through a vibrator 6 between the spools. The spools are mounted upon the upper ends of shafts 7, on whose lower ends are fixed bevel-gears 8 9 to mesh with bevel-pinion 10 11, fixed upon a transverse horizontal driving-shaft 12, which is movable endwise to bring either set of gears into mesh. The shaft 12 is held in either of its extreme positions by means of a yielding detent mechanism comprising a collar 13, fixed upon the shaft and having a peripheral groove 14, in which one end 15 of a lever is inserted, said lever being pivoted at 16 upon the framework and having in its upper end notches 17

18. An arm 19, also pivoted on the framework and pulled down by a spring 20, is provided with a roller 21 to engage said notches, whereby the shaft 12 is yieldingly held against accidental displacement. The shaft is rotated by means of a ratchet-wheel 22, operated by a pawl 23 at either type stroke. The wheel 22 is fixed to a gear 24, which is in mesh with a pinion 25, fixed upon the shaft 12, the gear 24 being of sufficient width to accommodate the axial movements of the pinion 25. When the ribbon is all paid off from either spool—as, for instance, spool 4—it

calls into action means for shifting the driving-shaft 12 longitudinally, so as to disconnect the bevel-gears in one pair, as 9 11, and reconnect the gears in the other pair, as 8 10. For this purpose the ribbon is passed around a post 26, which is fixed upon a spool-cup 27, the latter being revoluble concentrically with the spool-shaft 7. The post 26 is placed forward of the spool-core, and the ribbon stretches rearwardly from said post to the vibrator, thus enabling the pull on the ribbon (caused by the continued winding of the full spool 5) to turn the cup 27, the latter being fixed upon an arm or pair of arms 28. A sleeve or hollow shaft 29 surrounds the spool-shaft 7 and carries the arm 28 and cup 27, and of course is rotated by the movement of the ribbon just described. At its lower end the sleeve 29 carries a collar 30, having formed thereon a cam 31, which during the rotation of the sleeve engages a cam 32, formed on a finger or plate 33, and cams the latter downwardly. Said plate or finger is pivoted at 34 upon the framework and at its tip is bent downwardly at 35 and shaped to match the adjoining worm fixed upon the shaft 12. There are two of these worms, 36 formed right and left and designated as 36 37. When the finger 33 is cammed down, as seen in dotted lines, it engages the worm 36, and the latter, owing to the rotation of the shaft 12, cams the latter endwise, so that the bevel-gear 11 moves out of mesh and the bevel-gear 10 into mesh. Thereupon spool 4 begins to wind, and the spool-cup, the hollow shaft 29, and the cam 31 are returned to normal position by a spring 38, the finger 33 being elevated by a coiled spring 39, which is placed between the same bracket 40 which carries the spool-shaft.

It will be understood that when the ribbon is all wound off from the spool 5 similar operations take place to move the shaft 12 in the opposite direction, so that the ribbon will rewind on said spool.

Variations may be resorted to within the scope of my invention and portions of my improvements may be used without others.

Having thus described my invention, I claim—

1. In a type-writing machine, the combination with a pair of ribbon-spool shafts and a driving-shaft movable endwise to connect

with said spool-shafts in alternation, of worms upon said driving-shaft, normally idle fingers movable into engagement with the worms, cams mounted concentrically with the spool-shafts for forcing said fingers into engagement with the worms, and parts mounted upon said cams in position to be engaged by the ribbon.

2. In a type-writing machine, the combination with a pair of vertical shafts for winding the ribbon, of a horizontal driving-shaft movable endwise to connect with either of said vertical shafts, worms upon said driving-shaft, normally idle fingers pivoted upon the framework so as to be movable into engagement with said worms, cams for operating said fingers, loose sleeves upon said vertical shafts, said cams being secured to the lower ends of said sleeves, and arms projecting from the upper ends of said sleeves and having parts in position to be engaged by the ribbon.

3. In a type-writing machine, the combination with a pair of vertical shafts for winding the ribbon, of a horizontal driving-shaft movable endwise to connect with either of said vertical shafts, worms upon said driving-shaft, normally idle fingers pivoted upon the framework so as to be movable into engagement with said worms, cams for operating said fingers, loose sleeves upon said vertical shafts, said cams being secured to the lower ends of said sleeves, and arms projecting from the upper ends of said sleeves and having parts in position to be engaged by the ribbon; and ribbon-spool cups fixed upon said arms.

4. In a type-writing machine, the combination with a pair of ribbon-spool cups, of a pair of ribbon-spool shafts, said cups mounted concentrically with said shafts, a driving-shaft movable endwise to connect with either of said shafts, cams connected to said cups to be moved thereby, fingers movable by said cams, worms upon said driving-shaft engageable by said fingers, and a yielding detent for said driving-shaft.

5. In a type-writing machine, the combination with a pair of ribbon-spool shafts, of a driving-shaft movable endwise to engage with either spool-shaft, a pinion upon said driving-shaft, a gear in mesh with said pinion, and a ratchet-wheel fixed to said gear and immovable in axial direction; a yielding detent for said driving-shaft, worms upon said driving-shaft, and ribbon-controlled means for engaging said worms.

6. In a type-writing machine, the combination with a pair of upright ribbon-winding shafts, of spool-cups, the shafts being revoluble independently of said cups, and the latter being movable by the ribbon, sleeves upon which said cups are fixed, said sleeves surrounding said shafts, and the latter being revoluble independently of the sleeves, cams upon the lower ends of said sleeves, fingers

pivoted upon the framework and having projections engageable by said cams, returning-springs for said fingers, a driving-shaft movable endwise to engage either of said spool-shafts, worms upon said driving-shaft engageable by said finger, and a yielding detent for said driving-shaft.

7. In a type-writing machine, the combination with a pair of upright ribbon-winding shafts, of spool-cups, the shafts being revoluble independently of said cups, and the latter being movable by the ribbon, sleeves upon which said cups are fixed, said sleeves surrounding said shafts, and the latter being revoluble independently of the sleeves, cams upon the lower ends of said sleeves, fingers pivoted upon the framework and having projections engageable by said cams, returning-springs for said fingers, a driving-shaft movable endwise to engage either of said spool-shafts, worms upon said driving-shaft engageable by said finger, and a yielding detent for said driving-shaft, a pinion upon said driving-shaft, a gear in mesh with said pinion but immovable in axial direction, and a ratchet-wheel fixed to said gear.

8. In a type-writing machine, the combination with a pair of upright ribbon-winding shafts of spool-cups, the shafts being revoluble independently of said cups, and the latter being movable by the ribbon, sleeves upon which said cups are fixed, said sleeves surrounding said shafts, and the latter being revoluble independently of the sleeves, cams upon the lower ends of said sleeves, fingers pivoted upon the framework and having projections engageable by said cams, returning-springs for said fingers, a driving-shaft movable endwise to engage either of said spool-shafts, worms upon said driving-shaft engageable by said finger, and a yielding detent for said driving-shaft, and springs for returning said cups to normal positions after being moved by the ribbon.

9. In a type-writing machine, the combination with a ribbon-spool shaft and a driving-shaft movable endwise to connect with said spool-shaft, of a worm upon said driving-shaft, a normally idle finger movable into engagement with the worm, a cam mounted concentrically with the spool-shaft for forcing said finger into engagement with the worm, and a part mounted upon said cam in position to be engaged by the ribbon.

10. In a type-writing machine, the combination with a vertical shaft for winding the ribbon, of a horizontal driving-shaft movable endwise to connect with said vertical shaft, a worm upon said driving-shaft, a normally idle finger pivoted upon the framework so as to be movable into engagement with said worm, a cam for operating said finger, a loose sleeve upon said vertical shaft, said cam being secured to the lower end of said sleeve, and an arm projecting from the upper end of

said sleeve and having a part in position to be engaged by the ribbon.

11. In a type-writing machine, the combination with a ribbon-spool cup, or a ribbon-spool shaft, said cup mounted concentrically with said shaft, a driving-shaft movable endwise to connect with said shaft, a cam connected to said cup to be moved thereby, a finger movable by said cam, a worm upon said driving-shaft engageable by said finger, and a yielding detent for said driving-shaft.

12. In a type-writing machine, the combination with a ribbon-spool shaft, of a driving-

shaft movable endwise to engage with the spool-shaft, a pinion upon said driving-shaft, 15 a gear in mesh with said pinion, a ratchet-wheel fixed to said gear and immovable in axial direction; a yielding detent for said driving-shaft, a worm upon said driving-shaft, and ribbon-controlled means for engagement 20 with said worm.
